US00D980583S

(12) **United States Design Patent** (10) **Patent No.:** **US D980,583 S**
(45) **Date of Patent:** **** Mar. 14, 2023**

(54) **LED MASK**

(71) Applicant: **Zhongfa Li**, Ji'an (CN)

(72) Inventor: **Zhongfa Li**, Ji'an (CN)

(73) Assignee: **Zhongfa Li**, Ji'an (CN)

(**) Term: **15 Years**

(21) Appl. No.: **29/851,530**

(22) Filed: **Aug. 30, 2022**

(51) LOC (14) Cl. **02-02**

(52) U.S. Cl.

USPC **D2/741**; D21/660

(58) **Field of Classification Search**

USPC **D2/741**; D21/660

CPC **A41G 7/00**

See application file for complete search history.
